PLACQUES FOR CONFECTIONERY MACHINES

Max M. Guggenheim, New York, N. Y., assignor to National Equipment Corporation, New York, N. Y., a corporation of New York

Original application February 2, 1951, Serial No. 209,126, now Patent No. 2,704,519, dated March 22, 1955. Divided and this application November 9, 1954, Serial No. 467,718

10 Claims. (Cl. 198—108)

This invention has reference to machines for making candy or confectionery and more particularly the means by which the candies or confections are carried or conveyed for a substantial distance to enable the same to cool or set before being packed in boxes or other containers.

This application is a division of my co-pending application Serial No. 209,126, filed February 2, 1951 and now Patent No. 2,704,519.

In machines of this character the candies are conveyed from an enrober or coating machine and are received upon a flexible sheet referred to in the trade as a "plaque," the plaque being carried by a tray which is moved by chains through a lengthy and tortuous path within an enclosure in which the temperature is maintained at a suitable low degree to facilitate cooling and hardening of the candies.

At the end of its travel, each tray is arranged to have the plaque which it carries, as well as the candies borne by the plaque, moved from off the tray. The candies which leave the plaque, and which are at this time hardened or set, are carried off on a conveyor belt adjacent to a packing table where they are removed and packed in boxes. The plaque from which the candies have been removed, and which has been stripped from off its tray, is moved downwardly and thence rearwardly to the entrance end of the machine where it is again brought up to receive another supply of candies and then moved to a position upon another tray which again carries the plaque through the cycle as above described.

It is an object of the invention to provide an improved plaque construction; to provide means on each tray for easily engaging a rod at the forward end of the plaque to thereby position the plaque on the tray and maintain the same properly positioned thereon during the travel of the tray, yet permit ready separation of the plaque from the tray at the outlet end of the machine without requiring a lifting movement of the plaque.

In the accompanying drawing, wherein an illustrative embodiment of the invention is disclosed,

Fig. 1 is a top plan view of a tray with a plaque supported on the same;

Fig. 2 is a longitudinal sectional view through the tray;

Fig. 3 is a top plan view of one end of a plaque showing the rod carried by the same, and the means on the tray for engaging the rod to hold the same in position on the tray;

Fig. 4 is a sectional view, taken substantially on the line 4—4 of Fig. 3, looking in the direction of the arrows;

Fig. 5 is a view of the structure of Fig. 4, looking at the same from the right;

Fig. 6 is a longitudinal sectional view through one end of the plaque and the rod carried by the same;

Fig. 7 is a vertical sectional view through mechanism at the outlet end of the machine, showing the rod on the plaque in position to be engaged by conveyor chains and stripped from the tray; and

Fig. 8 is a similar view, showing the plaque partly

2

stripped from the tray; the candies being moved from the plaque onto a conveyor belt and the plaque being moved downwardly preparatory to movement to the forward or inlet end of the machine.

In a machine of the type in which the improved plaque is employed, candies or confections are coated or enrobed with a chocolate or other coating by means of an enrober and said coated candies are then received from the chain or link conveyor of the enrober upon a moving plaque 3, the moving plaque being at this time supported on a plate. The candies passing from the conveyor to the plaque, are received on the plaque as the same is travelling toward a tray generally indicated at 4 in Figs. 1, 7 and 8, the construction of which is disclosed in Fig. 1. The tray 4 is also moving in the same direction as the plaque, but the plaque is moved at a greater speed than the tray and overtakes the tray and is deposited thereon and thereafter the plaque and tray are moved together as a unit until they become separated at the location where the candies are removed from the plaque.

The plaque is composed of a sheet of flexible material, such as fabric, plastic or even heavy paper and the construction of one of the plaques is more clearly seen in Figs. 1 to 6. The flexible body 5 of the plaque is of a size to enable it to almost completely cover the top 6 of the tray 4, and at its forward end the sheet or body 5 of the plaque 3 is attached by the rivets 8 to a transversely-extending flat metal strip 7 which extends for the width of the sheet 5. Said strip maintains the sheet flatly and smoothly and is provided at its forward edge with an overturned flange 9 which takes over the forward flanged edge of a channel strip 10 that encloses a substantial portion of a transverse rod 11 as well as a part of the plaque 3. Rivets 13 extending through the strips 7 and 10 and through the rod securely maintain the rod in place, with the opposite end portions 12 of the rod 11 extending well beyond the longitudinal edges of the sheet 5 as clearly seen in Figs. 7 and 9. The location of the rod 11 within a channel strip 10, with a flange of the strip extending forwardly and stiffening the forward edge of the plaque, holds the front end of the plaque against folding or curling under the body of the plaque during travel and use of the plaque. The curled or overturned flange 9 provides a protective element for the front end of the plaque.

The trays 4 which support the plaques and the confections carried thereon, are of the construction shown in Figs. 1 and 3, wherein it will be noted that each tray is provided with the two longitudinal side bars 14 of angular shape in cross-section, said side bars being maintained in the desired spaced relation by means of the spaced cross-pieces 15. The cross-pieces 15, which may be channel-shape in cross-section, are attached to the body or flat plate 6 of the tray.

At the forward end of each tray and on the longitudinal side bars 14 thereof, are the retaining elements 16 for the plaque. Each of these retaining elements 16 consists of a block 17 formed with a channel or slot 18 extending through it, said channel or slot flaring as shown at 19 at its entry end to facilitate the ready admission of the ends 12 of the rod 11 of the plaque into the slot. Two spring-pressed locking elements 20 are provided in each of the slots 18, said locking elements permitting the rod-ends 12 to be readily forced into the slot and thereafter become located between them to hold the plaque against inadvertent shifting movement on the tray until it is desired to remove the plaque from the tray in a manner to be later described.

Each of the trays carrying a plaque with the candies thereon is moved through a lengthy path of travel by conveyor chains 21 to which each tray is connected at a central point by the lugs 22 fastened to the side bars 14 of

the tray. At its opposite ends each of the side bars 14 is provided with guide pins 23 which engage rails (not shown) but serving to maintain the trays and their contents horizontal or level during all phases of travel of the trays.

The tray 4 carrying a plaque 5 in the position shown in Figs. 1 and 3 wherein the end portions 12 of the rod 11 are located between the locking elements 20, is moved through a relatively lengthy and tortuous path of travel through a cooling chamber and finally is brought downwardly to the position shown in Fig. 7.

As the plaque and tray continue their downward movement, the rod 11 of the plaque contacts with cam plates 120 which engage behind the end portions 12 of the rod and tend to hold the rod and plaque while reverse movement of the tray in the direction of the arrow 99 disengages the rods from the retainers 16, and maintains the rod in position to become engaged by the lugs 44 on chains 45 which draw the plaque downwardly while the candies 46 are moved from the plaque onto a conveyor belt 79 (Figs. 7 and 8) to the packing table where the same are packed in boxes.

As the rod 11 becomes thus engaged by the cams 120 and held at a point of engagement by the lugs 44, the tray begins its return movement to the left as indicated by the arrow 99, and this causes the retainers 16 to be pulled from off the rod 11 which is then held by the cams 120 in the proper position for engagement by the lugs 44 of the chain 45 to draw the plaque downwardly, as shown in Fig. 8.

From the foregoing, the operation of the apparatus will now be readily understood. The candies issuing from the enrober are carried therefrom on a conveyor and are received from said conveyor on the plaque 3. The plaque 3 carrying the candies continues its movement toward the right, until it overtakes the moving tray and is coupled to the tray by the engagement of its rod 11 in the retainers 16 and brought to rest on top of the tray. The tray and plaque carried thereon, and now moved as a unit, are then elevated and carried by suitable conveying means through a cooling chamber and then brought downwardly as indicated by the arrow 42 (Fig. 7) to a point where the rod 11 on the plaque is engaged by the lugs 44 on the chains 45 and drawn from the retainers 16 on the tray. The candies are then directed from the plaque to the belt 79 and the plaque is drawn downwardly past the edge 76 of the plate 77, the plate 77 having been moved to its closed position shown in Fig. 8 and relative to guide piece 78 after the rod on the plaque has been moved past it.

It will be noted that the engagement of the ends of the plaque rod with the retainers 16 on the tray, as well as the disengagement of the rod from these elements, is done by straight-line movement of the rod and without lifting movement of the rod. Candies borne by the plaque are often soft and must not be subjected to shocks in order to prevent distortion or misshaping of the candies. Hence, the elevating and dropping movement of the forward end of a candy-bearing plaque, as has been done by prior constructions, is completely avoided by the described structure.

Having described one embodiment of the invention, it is obvious that the same is not to be restricted thereto, but is broad enough to cover all structures coming within the scope of the annexed claims.

1. In a machine of the character described, a movable tray, retaining means at one end of the same, said retaining means having slots open at both ends, a plaque having a rod extending across it at its forward end, said rod having end portions for reception in the slots through one end of the same and for exit out of the opposite end, and spring detents in spaced relation in the slots for engaging the ends of the rod between them and retaining the same in the slots.

2. In a machine of the character described, means for separating a plaque from a supporting tray comprising retaining means on the tray, said retaining means having open-ended slots, the slots being flared at one end, a plaque having a rod provided with end portions for entry through the flared ends and into the slots, spring detents in spaced relation in the slots for removably retaining the ends of the rods in the slots, and cam means for engaging behind the end portions of the rod and holding the plaque against movement while the tray is moved away from the plaque and the end portions of the rod are moved out of the slots through ends of the slot remote from the flared ends through which rods were initially entered.

15 3. In a machine of the character described, a plaque comprising a flexible sheet having a rod extending across it near one of its ends, plates secured to the sheet and extending transversely across the plaque and embracing the rod between them, said plates having flanged forward edges extending to the forward edge of the plaque sheet, one of the flanges being bent over the forward edge of the other flange, and the rod having end portions extending beyond the side edges of the plaque sheet.

25 4. In a plaque as provided for in claim 3, wherein one of the plates is flat and the other plate is channel-shaped in cross-section, and the portion of the plaque sheet which extends between the plates is partly extended around the rod, and fastening elements extending through the rod and through the plates.

30 5. In a machine of the character described, a plaque having a rod extending across one end, the rod having ends projecting beyond the side edges of the plaque, a tray on which the plaque is deposited, the tray having side walls provided near one end with channeled blocks 35 formed with horizontal slots into which the ends of the rod are entered, each slot being flared at one end to facilitate entry of one of the ends of the rod into said slot, one of the walls of the slot being provided with a pair of spring detents between which an end of the rod becomes positioned when the rod is entered into the slot.

60 6. In a machine as provided for in claim 5, wherein the pair of spring detents is provided on the upper wall of the slot, with one of the detents being positioned near the flared end of the slot and the other detent located adjacent to the opposite end of the slot, the detents being spaced sufficiently far apart to permit of the entry of an end of the rod between them.

7. In a plaque, a flexible sheet constituting the body of the plaque, a stiff strip extending transversely of the sheet adjacent to one end of the same and across the opposite face of the sheet and disposed co-extensively with the strip, a rod located between the strip and channel member and between a portion of the sheet and strip, and fastening means for securing the strip, the channel member and the rod together in the relationship described, said fastening means including elements extending through the rod.

65 8. In a plaque as provided for in claim 7, wherein the means for securing the channel member, strip and rod together, includes a curled flange projecting integrally from the strip and extending over an edge of the channel member and forming a protective forward edge for the body of the plaque.

9. In a machine of the character described, a plaque supporting tray having its side walls provided near one end with channelled blocks, a plaque for reception on top of said tray, said plaque having a rod at one end, each of said blocks being provided with a horizontally-extending slot open at both of its ends so that the ends 70 of the rod can enter through one end of each slot and be moved out through the opposite end of the slot, the inlet end of the slot being flared to facilitate entry of the plaque rod into the slot, one of the walls of the slot being provided with a pair of spring detents between which an end of the rod becomes positioned when the rod

is engaged in the slot, and means for causing movement of the rod ends into and out of the slots without applying a lifting movement to said rod ends.

10. In a machine as provided for in claim 9, wherein the pair of spring detents is provided on the upper wall of the slot, with one of the detents being located near the flared entrance end of the slot and the other detent located near the opposite open end of the slot, the detents being

spaced sufficiently far apart to permit of the entry of the end of the plaque rod between them, the detents preventing inadvertent movement of the plaque rod out of either open end of the slot, but permitting movement of the rod out of the exit end of the slot without requiring lifting movement of the rod.
